GUSTAF DALÉN, OF STOCKHOLM, SWEDEN.

INCANDESCENT GAS FLASH-LIGHT APPARATUS.

1,320,209.

Specification of Letters Patent.

Patented Oct. 28, 1919.

Application filed July 31, 1914. Serial No. 854,237.

To all whom it may concern:

Be it known that I, GUSTAF DALÉN, engineer, residing at Skärsätra, Lidingön, Stockholm, Sweden, have invented certain new and useful Improvements in Incandescent Gas Flash-Light Apparatus, of which the following is a specification.

My present invention refers to improvements in incandescent gas flash light apparatus, and has for its object to make the incandescent body last for a longer time than hitherto has been the case.

It has been proposed when using a flash light apparatus in combination with an incandescent light burner, to place the pilot flame outside the incandescent body, in which case however the gas or gas air mixture escaping from the main burner, is compelled to pass through the incandescent body or net at each time the main flame is to be lighted. The incandescent body thus is filled with gas or gas air mixture which results in a small explosion, when the pilot flame lights the main flame, whereby the incandescent body is caused to vibrate, being thereby injured. As for establishing flash light signals the main flame is lighted and extinguished many times a minute, the incandescent body obviously is subject to a considerable strain. It has also been proposed to place the pilot flame inside the incandescent body or net, but even in this case a small explosion, causing vibrations of the incandescent body, takes place each time the gas, flowing out from the main burner, is lighted by the pilot flame.

Now the invention in question has for its object to obviate said inconvenience by omitting the pilot flame, feeding the main burner with unequal amounts of gas or gas and air mixture, a large supply of gas or mixture of gas and air producing a flame of sufficient size to contact with the incandescent body and cause it to glow and a small quantity of gas or mixture of gas and air producing a small flame which does not touch the incandescent body. As in both cases a flame is burning in the burner, there is no risk for explosion at each time the incandescent body is made glowing, and for this reason said incandescent body is caused to last for a longer period of time than when using a pilot flame.

Figure 1 on the accompanying drawing illustrates in side view, partly in section, an apparatus embodying the present invention.

Fig. 2 is a similar view of a modified construction of apparatus, and

Fig. 3 illustrates a plan of a flash light apparatus, the cover of which is removed, provided with a device, by means of which the same function is obtained as in the apparatus made according to Figs. 1 or 2.

In Fig. 1, 1 indicates a flash light apparatus of any suitable construction, comprising an automatically working valve, opening and closing the conduit 2, leading to the incandescent light burner 3 in certain intervals of time. 4 indicates the inlet pipe to the flash light apparatus, through which pipe gas or a mixture of gas and air is admitted to the flash light apparatus 1. 5 indicates a gas conduit, arranged between the supply pipe 4 and the burner conduit as a by-pass around the flash light apparatus 1, and adapted to supply a small amount of gas or gas air mixture to the burner 3, when the valve of the flash light apparatus shuts off the gas supply to the burner conduit 2. When said valve again opens the burner conduit, a larger amount of gas or gas and air mixture is supplied to the burner, whereby the small flame burning in the burner swells up to a full flame. Thus in said burner 3 according to the circumstances a small flame is burning, or a full flame, the latter making the incandescent body glowing.

Instead of being passed or conducted through a by-pass or gas conduit 5 the gas may be conducted through a by-pass around the valve in the flash light apparatus to the burner conduit 2, as shown in Fig. 3.

In Fig. 2, an apparatus is shown in which a small amount of gas or gas air mixture is supplied to the burner 3 from a receiver 7, which is connected by a pipe 5 with the burner conduit 2. To the flash light apparatus 1 gas is conducted in this case through the pipe 4, and air for establishing a complete combustion is supplied to the burner conduit through an opening 8. The receiver 7 is closed by means of a diaphragm 9 and is fed with gas and air mixture from the burner conduit 2 through the pipe 5 during the time when the flash light apparatus 1 supplies gas to the burner conduit 2. When the valve of the flash light apparatus shuts off said gas supply a small amount of gas and air mixture is fed to the burner from the receiver 7 through the conduit 5, so that the full flame, previously burning, will be

diminished and the incandescent body will not be glowing. A check valve 11 in the burner conduit 2 prevents the gas and air mixture from flowing out through the opening 8. The pipe 5 in Figs. 1 and 2 may be provided with a suitable throttling device.

In Fig. 3 10 indicates a by-pass, arranged around the valve 6 of the flash light apparatus, through which by-pass a small amount 10 of gas or gas air mixture is supplied to the burner conduit, when the valve 6 is shut.

Having now particularly described my invention and set forth in which manner the same is to be performed, what I claim is:

15 1. In a flash light apparatus, the combination of a gas receiving casing, a supply pipe for supplying gas from any source to said casing, a conduit for conveying gas from said casing, to a burner provided with
20 an incandescent body, a valve for opening and closing the opening from said casing to said conduit, means for introducing air into said conduit wherein it is mixed with the gas therein, and means independent of said casing for supplying a reduced quantity of
25 gas and air mixture in unchanged proportions to said conduit when the said valve closes said opening from said casing to said conduit.

30 2. In a flash light apparatus, the combination of a casing for receiving gas from a source of supply, a conduit extending from said casing to a burner, a valve which periodically opens and closes for controlling
35 the flow of gas from said casing through said conduit to the burner, the gas supplied to said burner being mixed with air, and means for supplying a reduced quantity of
40 gas and air mixture in unchanged proportions to said burner during the periods when said valve is in closed position.

3. In a flash light apparatus, the combination of a casing for receiving gas from a source of supply, a conduit leading from
45 said casing for conveying gas therefrom to a burner provided with an incandescent body, means for permitting air to enter said con-

duit where it is mixed with said gas, a valve for opening and closing the passageway from said casing to said conduit, a receiver 50 and a connecting passageway between the said conduit and the said receiver, said passageway having connection with the said conduit at a point between that where the air is introduced into said conduit and the 55 said burner for conveying a mixture of gas and air from and to the said conduit whereby when the said valve closes the passageway from the said casing to the said conduit a mixture of gas and air is supplied to the 60 latter and to the burner from the said receiver.

4. In a flash light apparatus, the combination of a gas receiving casing, a conduit for conveying gas from said casing to a burner, 65 provided with an incandescent body, and means for periodically supplying unequal amounts of a gas and air mixture in unchanged proportions through said conduit to said burner.

5. In a flash light apparatus, the combination of a gas receiving casing, a conduit for conveying gas from said casing to a burner, means for mixing air with said gas to produce a gas and air mixture and means whereby unequal amounts of the said gas and air mixture in unchanged proportions are supplied periodically through the said conduit to the said burner.

6. In a flash light apparatus, the combination of a conduit for supplying a mixture of gas and air to a burner, means for causing the mixing of air with the gas and means whereby unequal amounts of the said gas and air mixture in unchanged proportions 85 are supplied periodically through the said conduit to the said burner.

In testimony whereof I have affixed my signature in presence of two witnesses.

GUSTAF DALÉN.
